DRAFT CONTROL

William G. Johnson, Milwaukee, Wis.

Application November 28, 1947, Serial No. 788,415

7 Claims. (Cl. 267—1)

1

This invention relates to improvements in draft controls for furnaces and particularly to controls which will automatically close the damper and check the furnace after a predetermined lapse of time.

Many homes employ hand-fired furnaces the drafts of which are controlled by chains or other motion transmitting connectors or draft manipulating devices which lead from the basement to the first floor. It is the practice to charge the fire pot of the furnace with fuel and then open the drafts by raising the control chain or connector. This opens the draft in the ash pit door and closes the check draft establishing the draft through the fire pot. Often the householder forgets about the opening of the drafts and leaves the house unattended with the drafts fully open. The unchecked fire will soon burn at a high rate and overheat the entire heating system, creating a fire hazard. Even though no extraneous fire results from such overheating, the fire will usually burn itself out and the householder upon his return will have to build a new fire.

It is, therefore, an object of this invention to provide a draft control which will automatically close the draft after a predetermined lapse of time.

Another object of the invention is to provide a draft control which may be easily installed in the draft control chains or connectors of existing heating systems without change to the devices for manipulating such chains and connectors and holding them in fully open or closed position or selected positions therebetween.

A still further object of this invention is to provide a draft control which is simple and economical to manufacture.

These objects are attained by providing a unit comprising an elongated cylinder in which a piston is movable between predetermined adjustable limits of fully contracted and fully extended positions, its movement for a portion of its stroke from contracted to extended position being restrained and slow and for the balance of such stroke being unrestrained and rapid, and its movement toward contracted position being unrestrained and rapid, and by connecting such unit between sections of the draft control chain or other motion transmitting connector. When the draft control chain or connector is raised, the entire unit is raised and the draft opened. The weight of the draft then causes the unit to slowly elongate for a predetermined distance and thereafter to rapidly elongate. This keeps the draft

2

open for a predetermined time and then accomplishes a complete closing of the draft at the end of such time. When the draft control chain or connector is reset to closed position, the unit 5 rapidly collapses to its fully contracted length. The unit is installed by merely removing a section of the vertical run of the draft control chain or other motion transmitting connector and substituting the unit for such section by connecting 10 the piston and the cylinder respectively to the ends of the adjacent sections so created. Such substitution requires no change in the exciting indexing mechanisms of the draft manipulating device. After being initially adjusted, the safety 15 operation of the control is entirely automatic. It resets itself without any attention from the furnace operator every time the draft manipulating device or indexing mechanism is moved to closed position.

The novel features, which are considered characteristic of the invention, are set forth with particularity in the appended claims. The invention itself, however, both as to its organization and its method of operation, together with 25 additional objects and advantages thereof, will best be understood from the following description of a specific embodiment when read in connection with the accompanying drawing, in which:

30 Figs. 1, 2, and 3 are diagrammatic views of a furnace with a draft control embodying the invention installed in the draft manipulating device, each view illustrating various positions of the draft as will be hereinafter more fully described;

35 Fig. 4 is a sectional view and Figs. 5 and 6 are views partly in plan and partly in section of a draft control unit embodying the invention, each view illustrating various positions of the parts of the control as more particularly described herein; and

40 Fig. 7 is a sectional view taken on the line 7—7 of Fig. 5.

45 Referring to the drawings by reference numerals, the draft control unit, generally designated 10, is connected in the vertical run of a draft control chain 11, the operation of which opens and closes the draft 12 of a furnace 28. Any standard indexing mechanism (not shown) may be utilized to move the chain 11 from the closed position and secure it in the open position shown in Fig. 1. The unit 10, however, may be installed in other motion transmission connectors or draft manipulating devices, such as 50 flexible wires, rods, or the like. To install the 55

unit 10 in existing controls it is only necessary to remove from the manipulating device a section substantially equal to the length of the unit when fully collapsed and inserting the unit in lieu of such section and connecting it to each of the ends of the adjacent sections created by the removal of such section. It is, of course, preferable to install the unit in the vertical run of such manipulating device. However, the section where the unit is installed may vary considerably from the vertical so long as the liquid medium does not flow from the cylinder 13. In some installations it may be necessary to install in the manipulating device above the unit a stop ring or other abutment (not shown) which will limit the extent of the opening movement of the manipulating device so that the draft 12 will not be opened a greater amount than will be offset by the subsequent extension of the unit 10 to fully extended position. One of the elements of the draft control 10 is a hollow cylinder 13. The cylinder 13 is open at the top and closed at the bottom. It is sufficiently long to permit of enough relative movement between it and the piston 14 to allow the draft 12 to close when the unit moves from the contracted position shown in Fig. 4 to expanded position shown in Fig. 6. The piston 14 consists of a hollow cylinder open at both ends and provided with a ball type check valve 20. The opening through the piston provides a by-pass 15. The piston 14 has a loose fit in the cylinder 13 and is movable from the adjustable fully contracted position shown in Fig. 4 to the fully expanded position shown in Fig. 6. Lugs 16 at the top of the cylinder 13 form an abutment for determining the fully expanded position. The piston 14 is provided with connecting rods 17 which extend from the upper end of the piston and project above the top of the cylinder 13. The connecting rods 17 may be made of a single one piece of wire bent in U shape to form a bridge 18 which extends across the upper end of the by-pass 15 to hold the rods to the piston and to provide a connector for the retraction spring 19. The use of two connector rods 17 provides ample operating space at the top of the by-pass 15 for the ball valve 20. The ball 20 seats under the influence of gravity to form a check valve which freely opens when the piston 14 is moving toward contracted position and which closes whenever the piston 14 is moving toward the extended position. The upper ends of the connecting rod 17 are secured to a disk 21, the periphery of which extends beyond the outer confines of cylinder 13. To the cap 21 there may be secured a tubular member 22 which loosely telescopically fits over the cylinder 13 to provide a dust cap. The coiled tension retraction spring 19 telescopically fits with the by-pass 15 and is secured to the bottom of the cylinder 13. It continually urges the piston 14 toward contracted position. Eyes 23, attached to the bottom of the cylinder 13 and the disk 21, provide the means for connecting the unit 10 to the adjacent sections of the manipulating device such as chain 11. A collar 24 slidably fits around the cylinder 13 and is maintained in selected adjustable positions thereon by the action of a winged nut 25 threadedly mounted in such collar. The collar 24 provides an adjustable abutment which limits the downward movement of the dust cap 22 with respect to the cylinder 13 and hence determines the fully contracted position of the piston 14. The adjustment of this position determines the length of time that it will keep the

draft 12 open. A liquid medium of density and specific viscosity greater than air (at ambient temperatures) is carried in the cylinder 13 so that its level 26 lies substantially at the center of height of such cylinder. In practice light oils have been found practical. If other liquids are used the clearance between the piston and cylinder must be so proportioned to sufficiently restrict the flow of the liquid medium used to require a predetermined time to elapse during which the piston 14 is moving toward extended position.

The principle of the operation of the control 10 is that the piston 14, in moving from fully contracted to fully extended position, must pass through two mediums, one of which is of greater density and viscosity than the other and which are separated along a substantially horizontal plane positioned between the extreme limits of relative travel of such piston and cylinder. During the time that the piston is traveling in the medium of greater density and specific viscosity its movement will be retarded. However, when the piston emerges from that medium and starts to move in the medium of lesser density and specific viscosity its movement will be unrestricted and unretarded and therefore will move with greatly increased velocity. The purpose, of course, is to keep the draft open for an extended predetermined time and then to close it. The greater velocity at closing creates enough force of momentum to insure a tight closing of the draft.

It has been found practical, where oil is one medium and air the other, to provide the cylinder 13 with grooves 27 which extend downwardly from the top to a point substantially below the line of separation between the mediums. Oil has a tendency to cling to the surfaces of the cylinder 13 and piston 14 to maintain a seal even after a substantial portion of the piston 14 has moved above the level of the oil. The effect of the grooves 27 is to break down this seal and permit the piston 14 to freely move in the air after it has reached the intermediate position shown in Fig. 5.

When the unit 10 is installed as heretofore described in the manipulating device or chain 11, the draft control operates in the manner as hereinafter described. When the indexing mechanism (not shown) is moved to the "draft open" position, force is applied to the chain 11 and it, with the unit 10, is raised and the draft 12 moved to open position. This position is diagrammatically illustrated in Fig. 1. At that time the piston 14 and cylinder 13 are in the fully contracted position shown in Fig. 4. This contracted position has been previously determined and set by adjustably positioning collar 24. The setting determines the amount of travel of the piston in the oil necessary to have the desired time elapse, say, for example, twenty to twenty-five minutes, during which time it is practical for the draft 12 to be open. Such time will, of course, vary with different localities and seasons and with the differences in the natural suction of different furnaces. Immediately following the opening of the draft 12, the weight of the draft 12, or of a supplemental weight (not shown) if the draft does not happen to be sufficiently heavy, will cause the cylinder 13 to move downwardly with respect to the piston 14 against the tension of spring 19. Such movement takes place only insofar as the oil or other medium selected passes through the space between the piston 14 and cylinder 13.

Thus for greater than half of the total travel the downward movement of the cylinder 13 is very slow. As it moves it down, the level 26 of the oil also moves down, and when the parts are substantially in the position illustrated in Figs. 2 and 5, the level 26 of the oil has receded below the center of the piston 14 and the bottom of the piston 14 has reached the bottoms of the grooves 27. At this time the oil seal is broken and the cylinder 13 starts to drop with rapidly accelerating speed. This speed greatly increases when the oil level has receded entirely below the piston and the piston is then moving freely through the air or other medium of lesser density and specific viscosity. Consequently, the last part of the stroke is accomplished with enough speed to force the draft to a tightly closed position. The piston 14 and cylinder 13 are then in the relative positions illustrated in Fig. 6, the legs 16 preventing further movement. During all of these movements, of course, the spring 19 is stretched by the weight of the cylinder 13, the lower section of chain 11 or other manipulating device, and draft 12, and the control will stay in the position shown in Fig. 6 until the indexing mechanism for the chain 11 is moved to "draft closed" position. When this occurs, the force on the chain 11 is removed and the spring 19 draws the piston 14 and its associated parts down to the fully contracted position. During this movement the passage of the piston 14 through the oil is unretarded because the check valve 20 automatically opens. The control thus automatically resets itself in the position illustrated in Fig. 4 and is then ready to repeat the operation when the indexing mechanism is again moved to "draft open" position.

Although only one embodiment of the invention is shown and described herein, it will be understood that this application is intended to cover such changes or modifications as come within the spirit of the invention or scope of the following claims:

1. A draft control comprising an elongated cylinder the top of which is freely open to atmosphere, a piston movable in said cylinder within predetermined limits, a liquid medium of density and specific gravity greater than air partly filling said cylinder to restrain and retard the movement of said piston throughout a portion of its travel in one direction through said liquid medium, a valve permitting the motion of said piston to be unrestrained by said medium in the opposite direction of travel of said piston, said piston being restrained by the atmosphere and unrestrained by said liquid medium in its travel above said liquid medium, and means for inserting said control in a draft manipulating device.

2. A draft control comprising an elongated cylinder closed at one end and open at the other end, a fluid medium in said cylinder and filling substantially the lower half thereof, the upper half being open to atmosphere, a cylindrical hollow piston loosely slidably mounted in said cylinder and movable between said ends, a ball valve resting on and adapted to close the upper end of said piston whereby said piston unrestrainedly moves downwardly through said medium, the movement of said piston upwardly through said medium being slow and retarded by the restricted passage of said medium between said cylinder and said piston until the level of said medium has receded a substantial distance past the top of said piston, the upward movement of said piston thereafter being rapid and unretarded, and means for connecting said piston to one section of

a draft manipulating device and said cylinder to an adjacent section of said draft device.

3. A draft control comprising an elongated cylinder closed at one end and open at the other end, a fluid medium in said cylinder and filling substantially the lower half thereof, the upper half being open to atmosphere, a cylindrical hollow piston loosely slidably mounted in said cylinder and movable between said ends, a ball valve resting on and adapted to close the upper end of said piston whereby said piston unrestrainedly moves downwardly through said medium, the movement of said piston upwardly through said medium being slow and retarded by the restricted passage of said medium between said cylinder and said piston until the level of said medium has receded a substantial distance past the top of said piston, the upward movement of said piston thereafter being rapid and unretarded, means for connecting said piston to one section of a draft manipulating device and said cylinder to an adjacent section of said draft device, and means for adjustably limiting the downward travel of said piston.

4. A draft control for a furnace comprising a draft manipulating device provided with a substantially vertical run, a reservoir having its bottom connected to the top of a section of said run and its top open to atmosphere, a liquid medium partly filling said reservoir the remainder thereof being filled with atmosphere, a plunger slidable in said reservoir and having a by-pass and valve to permit said plunger to unrestrainedly move downwardly through said liquid medium, means interconnecting said plunger with the bottom of a section of said vertical run immediately above said first section, said plunger and said reservoir being spaced apart to slowly permit the passage of said liquid medium therebetween to retard the downward movement of said reservoir with respect to said plunger until the level of said liquid medium has receded below the top of said plunger whereupon said plunger will be retarded by the passage of air between said plunger and said reservoir and unretarded by said liquid medium, and abutment means for providing an extreme limit of downward movement of said reservoir with respect to said plunger.

5. A draft control for a furnace comprising a draft manipulating device provided with a substantially vertical run, a reservoir having its bottom connected to the top of a section of said run and its top open to atmosphere, a liquid medium partly filling said reservoir the remainder thereof being filled with atmosphere, a plunger slidable in said reservoir and having a by-pass and valve to permit said plunger to unrestrainedly move downwardly through said liquid medium, means interconnecting said plunger with the bottom of a section of said vertical run immediately above said first section, said plunger and said reservoir being spaced apart to slowly permit the passage of said liquid medium therebetween to retard the downward movement of said reservoir with respect to said plunger until the level of said liquid medium has receded below the top of said plunger whereupon said plunger will be retarded by the passage of air between said plunger and said reservoir and unretarded by said liquid medium, and abutment means for providing an extreme limit of downward movement of said reservoir with respect to said plunger, and spring means in said cylinder for urging said plunger downwardly through said liquid medium when the tension on said plunger supplied by said draft manipulating

device is released upon said device being moved from open to closed position.

6. A draft control comprising a draft manipulating device having adjacent sections, a reservoir connected to one of said sections, a plunger connected to the other of said sections, said plunger being slideable within said reservoir between predetermined limits, a liquid medium of density and specific gravity greater than air partly filling said reservoir, said plunger and reservoir having restricted space therebetween whereby the flow of said liquid medium between said plunger and reservoir is retarded as said plunger and reservoir are relatively moved by tension in said device while said plunger is below the level of said liquid medium, a vertical groove in one of said plunger or reservoir to provide an enlarged space therebetween for the remainder of the permissible relative travel therebetween while said plunger is above the level of said liquid medium whereby the flow of atmospheric air between said plunger and reservoir is unrestricted by the incidental clinging of said liquid medium to the surface of said plunger as said plunger and reservoir are relatively moved in said remainder by tension in said device, and a by-pass and valve therefor permitting said liquid medium to freely flow and allow said plunger to freely move relative to said reservoir when tension is released in said device.

7. A draft control comprising a draft manipulating device having adjacent sections, a reservoir connected to one of said sections, a plunger connected to the other of said sections, said plunger being slideable within said reservoir between predetermined limits, a liquid medium of density and specific gravity greater than air said reservoir,

partly filling said plunger and reservoir having restricted space therebetween whereby the flow of said liquid medium between said plunger and reservoir are retarded as said plunger and reservoir are relatively moved by tension in said device while said plunger is below the level of said liquid medium, a vertical groove in one of said plunger or reservoir to provide an enlarged space therebetween for the remainder of the permissible relative travel therebetween while said plunger is above the level of said liquid medium whereby the flow of atmospheric air between said plunger and reservoir is unrestricted by the incidental clinging of said liquid medium to the surface of said plunger as said plunger and reservoir are relatively moved in said remainder by tension in said device, a by-pass and valve therefor permitting said liquid medium to freely flow and allow said plunger to freely move relative to said reservoir when tension is released in said device, and resilient means carried in said cylinder for urging said last mentioned relative movement.

Certificate of Correction

October 9, 1951

WILLIAM G. JOHNSON

It is hereby certified that error appears in the printed specification of the above numbered patent requiring correction as follows:

Column 8, line 1, strike out "partly filling" and insert the same in column 7, line 37, after "air";
and that the said Letters Patent should be read as corrected above, so that the same may conform to the record of the case in the Patent Office.

Signed and sealed this 29th day of January, A. D. 1952.
